MANUFACTURE OF SLIDE FASTENERS

Louis M. Rabinowitz, New York, N. Y., assignor to
Lamar Slide Fastener Corp., New York, N. Y., a
corporation of New York

Application September 16, 1942, Serial No. 458,589

9 Claims. (Cl. 153—1)

This invention relates generally to the manufacture of slide fasteners or so-called zippers and is more particularly directed to a method and means for producing scoops or interlockable elements of such fasteners from preprocessed lengths of appropriate material, and successively clamping the scoops in spaced relation upon the usual tape, in a continuing operation, in the formation of the fastener stringers.

In accordance with standard practice, in the production of slide fasteners, wire or other suitable stock is passed between cooperating dies for deformation to produce a connected series of partially profiled scoops. This preformed stock is subsequently introduced to machines for completing the formation of the scoops and clamping them to the beaded portion of a tape in the production of the fastener stringers. However, the machines now employed for producing the stringers are of a more or less complicated design, with concomitant high installation and maintenance costs, which are necessarily reflected in the ultimate cost of the product to the consumer, the waste of material in the formation of the scoops, together with the limited production capacity of the machines being contributing factors in the fixing of such ultimate cost.

Therefore, the primary object of this invention is to generally improve the manufacture of slide fasteners and more especially to eliminate waste and increase the rate of production of the stringers in a simple and efficient manner so as to attain more economical production than is possible in the utilization of present methods of manufacture.

More specifically, it is an important object of this invention to provide a compact and dependable mechanism, capable of high-speed operation for automatically performing a series of co-related steps in a continuing operation thereof, for forming the scoops or interlockable fastener elements from preprocessed material and assembling them upon tape in their final form for producing the fastener stringers.

Another object of my invention is to provide a method and means for producing stringers for slide fasteners, as aforesaid, in which waste of the material from which the scoops are formed is eliminated, the material heretofore becoming scrap, in the functioning of existing mechanisms, being utilized in the practicing of my method in increasing the strength and rigidity of the scoops and the security of their interlocking engagement with the tape. By the employment of my method and mechanism in scoop production, lighter

gauge wire or other stock may be employed in their manufacture, with a resulting decrease in material costs, without detracting from the efficiency and durability of the fastener in which they may be incorporated.

It is also an object of my invention to provide a mechanism having the aforesaid advantages and characteristics, in which all of the steps necessary to the production of the stringer, from the severance of the partially formed scoops from the processed strip introduced to the mechanism, to the completion of the stringer, are performed in synchronized relation in a continuing operation of the mechanism at high speed, the novel and efficient coordination of the elements of the assembly insuring dependable and accurate functioning of the mechanism under such extreme operating conditions.

Other objects and advantages flowing from the practicing of my invention will become manifest as the description proceeds.

For the purposes of this disclosure, I have elected to show and describe a preferred mechanism for carrying my invention into effect. However, various structural changes may be made in my mechanism to meet different production and other requirements, within the purview of the appended claims.

In the drawing—
30 Figure 1 is a top plan view of my improved mechanism for producing stringers for slide fasteners in a series of synchronized steps of a continuing high speed operation.

Figure 2 is an end elevation of the machine shown in Figure 1.

Figure 3 is a transverse section on the line 3—3 of Figure 1.

Figure 4 is a longitudinal section on the line 4—4 of Figure 1.

Figure 5 is an enlarged sectional detail of the cooperating elements of the assembly for completing the formation of the scoops and attaching them to the tape.

Figure 6 is a view in perspective, partly broken, of the dies for severing the preformed scoops from the continuous lengths of previously processed stock, completing their formation and clamping them to the tape in successive steps in the operation of the mechanism.

Figure 7 is an enlarged detail, in elevation, of the means for arresting the operation of the dies for the progression of the tape through the mechanism to produce an area of demarcation between contiguous stringers.

Figure 8 is a top plan view of the structure of Figure 7; and

Figure 9 is a cross-sectional view of the mounting of the presser foot for feeding the strip of preformed material to the dies.

Referring now to the drawings in detail, in which like characters of reference are employed to designate similar parts in the several views, the preprocessed stock is introduced to the mechanism of the present invention from the left, as shown, in Figure 1, for the sequential performance of the several steps of the continuing operation in which the fastener stringer is produced. This preprocessed material may be flexible wire or other suitable stock which has been passed between male and female dies in a preceding independent operation, to deform the wire in producing a series of connected partially profiled or shaped scoops, the processed wire usually being wound upon a reel from which it is withdrawn, as required, in the operation of the stringer-producing mechanism.

In the functioning of the mechanism, the preprocessed stock is delivered or fed to the dies, including a compound die, which are effective in shearing the individual partially formed elements from the strip stock, the respective elements being subjected to further shaping in a succeeding step, the final shaping of the scoops and their clamping engagement with the bead of the stationary tape being concurrently effected in response to the functioning of the compound die, in the final step of the die operations. The tape, as herein shown, is drawn upwardly through the die area in a step-by-step or intermittent movement, for uniformly defining the spacing of the scoops thereon and periodically, as may be predetermined, the operation of the dies is arrested while the movement of the tape continues, to provide gaps between adjacent series of scoops affixed to the tape, within the area of which the tape may be severed to form individual stringers. Stringers of any desired length may be produced by appropriate adjustment of the die arresting means, as will become apparent. The operation of the mechanism is continuous, so that several thousand feet of preprocessed stock and the requisite yardage of tape for producing a required quantity of stringers may be run therethrough without interruption of the operation of the mechanism, as is frequently necessary in prior art mechanisms, the scoops being uniformly and accurately shaped without waste in the functioning of the cooperating dies.

The processed strip, indicate at *s*, as introduced to the machine, is moved to the dies in successive steps by frictional feed mechanism, including a corrugated contact plate 10 forming a part of the presser foot 12, the strip-engaging surfaces of the plate 10, preferably conforming to the contour of the opposed surfaces of the strip *s*. The presser foot 12 embodies an upright bearing portion 13, slotted as at 13a, the slot merging into a transverse annular bore for the reception of the conical or tapered ends of the studs 14, by means of which the presser-foot is mounted for rocking movement within the bifurcated standard 15 of the slide 16, reciprocable relative to the machine bed 11. An arm 17, fixed to the slide 16, carries a roller or cam follower 18 which is maintained in constant engagement with the periphery of the cam 19 by a spring 20 mounted on the pin 21 carried by the slide and a post 22 seated in the machine bed. A second spring 20a, supported between the fitting 15a, spanning the

bifurcated standard of the slide 16, and rigid therewith, and a pin 23, entered in the bearing portion 13 of the presser-foot and secured thereto by a set screw 23a, functions to tiltly dispose the presser-foot for frictional engagement of the contact plate 10 thereof with the opposed surfaces of the strip *s*. As the active surface of the cam 19, rotating with the shaft 24, engages the roller 18 to urge the slide 16 inwardly, the strip *s* is advanced toward the die position, in response to the frictional engagement of the contact plate 10 of the spring-canted pressure-foot therewith, the slide receding at the termination of the strip-feeding movement under the influence of the spring 20. In the recession of the slide, and the concurrent outward movement of the presser-foot, the latter is oscillated in opposition to the spring 20a, as the contact plate 10 traverses the strip *s* which is stationary during the interval in which the shearing die is functioning, as will become apparent.

As the preformed strip *s* is advanced to the die position through the bifurcated standard 15, which serves as a guide, the forward end thereof impinges against the stationary die 25 seated in the support 26 disposed transversely of the machine bed, a female or shearing die 27 slidably mounted in the block 28 reciprocable in said support 26, coacting therewith, to sever the individual scoop elements from the strip in the termination of its descending movement in impingement with the buffer block 29. This excursion of the die 27 is cushioned by a spring 29a interposed between the base of the recess 30a in the support 26 and a collar 30 on the rod 31 dependent from the buffer block for movement in the guide 32. The female punch or die, as will be noted, is biased toward the strip *s* by a compression spring 33 supported between the opposed surfaces of the die and the reciprocable block 28, the downward movement of the die being limited by the lug 34 traversing the slot 35 in said block. A second compression spring 36, seated in the support 26, abuts upon the arm 37 extending horizontally from the reciprocable block 28, to function in biasing the latter block upwardly to reset the punch or female die, in the upward excursion of the die actuating lever 38 which is rockable on the pin 39.

The lever 38 carries a cam roller 40 which is traversed by the eccentric cam 41 revolvable with the shaft 42, the upper end of said lever overlying the head of the block 28 and being threaded for reception of a set screw 38a disposed for engagement with the head of the block 28, to depress the block in the actuation of the die assembly as just described, in response to the actuation of said lever 38, as the cam follower 40 thereof is traversed by the active peripheral surface of said cam 41, the die 27 being raised out of engagement with the work in the upward movement of the block 28, as previously set forth.

Mounted in juxtaposition to the shearing die 27 for relative opposite reciprocation in a horizontal plane, are a pair of slides 43 and 44 on which are mounted dies 45 and 46. These latter dies, which will be hereinafter described in greater detail, are of the compound type and function to complete the formation of a scoop that has been severed from the strip *s* and clamp it to the bead *b* of the tape *t* in a single die action. The slides 43 and 44 are provided with cam rollers 47 and 48 maintained in engagement with the cams 49 and 50 rotating respectively with the parallel shafts 42 and 51, by the springs 52 and

53, the slides being urged inwardly in opposition to the springs 52 and 53, to function the supported dies 45 and 46, as their cam rollers are traversed by the active surfaces of said cams 49 and 50. See Figure 3.

The tape *t* upon which the scoops are secured in the operation of the dies 45 and 46, as aforesaid, is fed vertically through the die position, passing between suitable friction guide rollers, from a reel or other carrier located beneath the bed of the machine in conforming traversing engagement with a drum 54 fixed to the shaft 55, disposed transversely of the machine. Oppositely mounted on said shaft 55 is a toothed wheel 56 which is pawl actuated to effect rotation of the drum 54 in a step-by-step or intermittent movement. The actuating pawl 57, embodying a nose 57a sequentially engageable with the teeth of the wheel 56, is pivotally mounted beneath said wheel, as at 58, on an upright arm 59 of a slide 60, the nose of the pawl being retained in engagement with the teeth of the wheel 56 by a spring 61 attached to the pawl and to the arm of a post 62 rigid with the slide 60. This slide 60 also carries a cam roller, as at 63, maintained in contact with the face of the cam 64 mounted on the aforesaid shaft 42, by the spring 65, the outer end of the slide being supported by the idler 66. As will be seen from Figure 4, the active surface 64a of the cam 64 is conformed to impel the slide to the left, in opposition to the spring 65, to rotate the toothed wheel and the concentric drum 54 one step in each revolution of the shaft 42, the slide moving in the opposite direction, under the influence of said spring 65, as the roller rides the dwell of the cam, to position the pawl in engagement with the wheel 56 for the next rotative step thereof.

As will be apparent, the tape is advanced step-by-step, as just described, in synchronism with the functioning of the forming and clamping dies, the completed stringers, which are defined by gaps or blank spaces on the tape between adjacent series of scoops, produced as hereinafter described, traversing the drum to the take-off chute 67. A shoe 68, supported from an arm 69 mounted on a bracket 70 bolted to the bearing member 71 of the drum shaft 55, is biased against the periphery of the drum by a suitable spring 72, as shown in Figure 1, and functions to maintain the tape in frictional engagement with the drum in its passage thereover, the shoe cooperating with tape-engaging elements at the die position to maintain the tape sufficiently taut and in the correct attitude relative to the clamping dies, for the efficient performance of the clamping operation. These tape-engaging elements comprise a pair of oppositely disposed guides 73 and 74 located parallel to and beneath the clamping dies 45 and 46 (see Figure 5) the spacing of the opposed surfaces of the guides defining a path for the movement of the tape therebetween. The guide 73 is fixed relative to one surface of the tape, while the guide 74 is laterally adjustable relative to the opposite surface thereof, in engagement with the block 75. The block 75 is pivotally mounted, as at 76, in the bearing 77, a spring 78 connected to an axially projecting pin 79 on said block and to a hand adjusting screw 80, as at 80a, provides for variations in the tension of the spring 78, to regulate the pressure of the guide 74 upon the tape, so that the tape is yieldably retained in the requisite position for passage between the dies.

Since the tape *t* is continuous, as is also the

preformed strip *s* and the scoops are formed and clamped to the tape in a continuing operation, in order to produce fastener stringers of the desired lengths, without slowing down the rate of production, a simple and novel arrangement is employed for arresting the advancement of the strip *s* into the die position, by locking the female punch or shearing die 27 in its lowermost position, the die in this position gripping the strip in engagement with the buffer block and immobilizing it.

In its lowermost position, the legs of the die, indicated at 27a, straddle the raised surface 29b of the buffer block, so that the end portion of the strip *s* is clamped between the die and the buffer block surface 29b. The spring 29a biases the buffer block against the opposed surfaces of the die, causing the forward edge of the strip *s* to impinge against the stationary die 25, so that the strip cannot advance. While the strip is held against advancement, as pointed out, the plate 10 of the presser foot 12 frictionally glides over the surfaces of the strip, during the continuing operation of the strip-feeding elements, as heretofore described. Preferably, the plate 10 is of softer material than that of the strip *s*, to eliminate the possibility of abrasion of the preformed surfaces thereof, in the movement of the strip thereover, while it remains stationary. As heretofore pointed out, while the movement of the strip *s* is arrested, the intermittent advancement of the tape *t* continues, as explained, but since no further scoop elements are supplied for fixation to the tape, when the strip movement ceases, a gap or blank area in the tape results.

The mechanism for arresting the operation of the die 27 and the movement of the strip *s* is actuated from the shaft 51 and includes a bell-crank lever pivotally mounted, as at 82a, on the top of the standard 83, for rotation in a horizontal plane, parallel to that of the head of the striker-screw 38a of the die-actuating lever 38. The minor arm 81 of said bell-crank, which is offset below the major arm 82 thereof, being apertured for mounting a clevis fitting 84 thereon for relative rotative movement on the axis of the attaching stud 83a. A turnbuckle 84a connects the clevis 84 to the crank end 85 of the arm 86 fixed to the shaft 87, horizontally mounted in the aforesaid standard 83, a lever 88, likewise rigid with said shaft, carrying a roller 89 disposed for riding the link-chain 90, the roller being held in contact with the chain by the action of the spring 91 connected to the crank 85 and a pin 92 seated in the top of said standard, which is slotted adjacent the pin, as at 83b, to permit the arm to extend thereabove, as shown in Figure 7. The chain 90 traverses the angularly offset sprockets 93 and 94, the sprocket 93 being fixed to the shaft 95 rotating in bearings in the standard 83, while the sprocket 94 is adjustably mounted on the machine bed, as at 96 to facilitate chain adjustments and replacements. The shaft 95 is driven from the shaft 51, a worm or spiral gear 97 carried by the axial extension 51a of the latter shaft, in mesh with the worm gear 98, transmitting torque to the shaft 95 through the gear 98, pinion 98a mounted on shaft 95a and gear 99 fixed to said shaft 95, inwardly of the sprocket 93.

Mounted on adjacent links of the chain 90, are a pair of camming elements 100, the effective surfaces of which are disposed for engagement by the roller 89, as the chain 90 moves upon the sprockets 93 and 94. In its normal, non-effective position, the disposition of the bell-crank

lever is such that the outer end of the major arm 82 is in radially spaced relation to and clear of the head of the striker-screw 38a (see Figs. 1 and 2), the roller 89 riding upon the links of the chain 90, as the shaft 95 is driven in timed relation to the performance of the die operations, requisite for severing a predetermined number of scoop elements from the strip s. However, when the leading cam element 100 engages beneath the roller 89, the shaft 87 is rocked counterclockwise, the concurrent movement of the arm 86, in opposition to the spring 91, effecting clockwise rotative movement of the bell crank lever to locate the end of its major arm 82 in engagement with the head of the striker-screw 38a to hold the lever 38 inoperative in its die-actuating position, as the cam 41 continues to rotate beneath the roller 40. The length of the gap or blank area in the tape is determined by the interval during which the arresting mechanism is in functioning condition, this period being controlled by the number of cam elements that are associated with the chain 90, for sequential engagement with the roller 89; also the length of the stringers may be varied by using chains of different lengths, with the appropriate adjustment of the sprocket 94 for the operation of the mechanism as described.

Another important feature of the present invention resides in the novel method of making a stringer from a preformed continuous scoop strip corresponding to strip s as herein described and shown in enlarged perspective in Figure 6. The form shown comprises adjacent humped portions 101 defining opposite corresponding cavities 102 to provide the requisite male and female elements of cooperating scoop units. Arms 103 are formed in the sides of strip of the configuration shown, the individual scoop elements being sheared or cut from the continuous strip s, as will be described in connection with Figure 6, into the individual forms shown at 104 and 105.

The punching dies 25 and 27 are shaped to include a single humped section 101 and the longitudinally extending jaws, tongues or wings 106. Elements 104 and 105 are the intermediate forms of the scoops prior to the clamping thereof on bead b of tape t by clamper dies 45, 46. Scoop 105a is shown clamped upon tape t in its final form, with tongues 106 gripped about bead b and with the side undulations 103a absent therefrom, these latter surfaces being swaged into the scoop element, as it is smoothed out into the final required shape, in a manner to be described.

The continuous scoop strip s is advanced against stationary punch die 24 in the manner previously described, the wings 106 of the forward end of strip s encircling complementary projecting section 25a of die 25. Coacting female die 23 is shown in broken lines to avoid confusion. As previously described, female punch 27 is vertically reciprocated in block 28 (Figure 5) and is slidable in the block through grooves 27'.

The female die is recessed, as at 27b, to coact with the protruding portion 25a of male die 25. As female punch 27 descends, legs 27a thereof over-lap the sides of strip s and force the inner strip downward against protruding section 25a of die 25. A clean shearing action is effective against punching surface 25a to smoothly shape the scoop elements in the form shown at 104.

Scoop element 104 is shown intermediate of scoop element 105 being clamped about tape t and the unsevered end of continuous strip s. In

the illustrated form, one scoop element 104 is in reserve and free between the scoop element 105 in process of being clamped about the bead of tape t and the scoop strip s, insuring better physical separation of the dies 25, 27 and former-clamper dies 45, 46. It is to be understood that my invention may equally well be practiced with more than one intermediate scoop element (corresponding to 104) between the punch dies and the former-clamper dies; and conversely, that the invention may be practiced without any intermediate scoop elements, with the shearing or punching and former-clamper operations following in juxtaposition.

Scoop element 105 is shown with its wings 106 enclosing bead b of tape t, just prior to the clamping operation of dies 45 and 46. These latter dies are arranged to move together laterally against the beaded portion of the tape as indicated by the arrows in Figures 5 and 6.

After dies 45, 46 are brought together and scoop 105 is clamped onto tape as shown, the dies 45, 46 are reversibly actuated, as previously described, permitting the upward advancement of tape t in an amount corresponding to predetermined spacing between zipper elements 105a thereon. During the advancement of tape t, female punch 27 is reciprocated upwards, permitting buffer block 29 to lift the free end of scoop strip s, the strip being advanced by the intermittent frictional feed mechanism, as previously described, to locate the free end thereof against intermediate scoop element 104, which in turn is moved against bead b of tape t, since scoop element 105 has previously been advanced upwards to the position of the scoop shown at 105a in Figure 6. The female die 27 then descends, coacting with punch die 25 to sever another scoop from the end of strip s, corresponding to scoop 104 in Figure 6.

As will be observed, the clamping dies 45, 46 are of the compound type, the opposed ends 45a, 46a of the upper die sections 110, being conformed to perform the final shaping of the scoops concurrently with the pressing of the wings 106 into gripping engagement with the bead of the tape, the undulations 103a in the sides of the elements 103, as presented to the die faces, being displaced inwardly in this operation into the wings to increase their cross-sectional area and produce the scoop in its ultimate form, as at 106. The opposed ends 45b and 46b of the lower die sections 111 cooperate to initially clamp the scoop elements, as at 105, to the tape bead and conform the wings for the completion of the forming and clamping operation, in the upward progression of the element to the clamping position, it being manifest that as the clamping operation is being performed with respect to the uppermost element in the die position, the next below element is being partially shaped in the preliminary clamping of the element to the tape preparatory to its upward advancement.

It is to be understood that further die sections 65 may be incorporated in the set of dies 45, 46 to perform other functions or to separate this function from the intermediate shaping and final smoothing operation. The shaper die surfaces 45a-46a, are of such length that they envelop entire length of each side of the scoop being mounted, so that substantially the entire sheared scoop blank is shaped thereby.

The plurality of operations by the dies 45, 46, operated in synchronism with the motivation of tape t and scoop strip s, simplifies the construc-

tion of the machine as a whole, and minimizes the space requirement, and reduces the expense of its construction. The individual sections of the clamer dies for intermediately shaping the scoops and imparting to them their final form in clamped position on tape *t* is accomplished in stages one above the other, spaced by the predetermined distance of scoops on tape *t*. The continuous scoop strip *s* is rolled or otherwise preformed into the described shape to permit the severing of the scoops corresponding to the shape shown at 101 in Figure 6 in a single punch operation of the dies corresponding to 25, 27. One or more, or no intermediate scoops corresponding to 101 may be stored between punch dies 25, 27 and the shaper-clamer dies 45, 46.

As will be seen from Figure 1, the cam shafts 24 and 51 are driven from the shaft 42 through bevel gears 112, the shaft 42 having a pulley 113 keyed to the outer end thereof, formed for the reception of a V belt 114, connectable to a pulley on a suitable motor (not shown) or other power transmitting means. The three shafts are journaled in suitable anti-friction bearings 115, for rotation in the same horizontal plane, in association with the usual removable retainers 116, for facilitating the assembly of the drive. This arrangement provides a compact, rigid layout which is extremely durable under high speed operating conditions and also expedites the effecting of such adjustments and repairs as may be required, in which connection it may be noted that the cam 41 which operates the die-actuating lever 38 is carried by the driving shaft 42, so that the heaviest load is imposed directly on this shaft, with the attendant operational advantages and the elimination of possible backlash in the gearing, as would result in sustained operation were this load imposed on a gear driven shaft, as in prior art devices.

It is obvious that various changes and modifications may be made in the method and details of the exemplification without departing from the general spirit of the invention as set forth in the following claims.

I claim:

1. A machine for forming lengths of tape mounting groups of uniformly spaced scoops for slide fastener assembly, comprising a cutting device including a stationary and a vertically reciprocable shearing die, shaping and clamping dies associated with said cutting device to provide a die station in said machine, means for intermittently advancing a strip of embryo fastener elements to said station, for successive severance therefrom of individual elements to be progressively introduced to said shaping and clamping dies for conversion into scoops, said strip-advancing means comprising a reciprocable device and a rockably mounted member associated therewith for frictionally engaging said strip during the movement of the reciprocable device in one direction to intermittently advance the strip toward the die station, means for feeding a beaded tape through said station in a continuous uniform step-by-step movement for the clamping of the severed elements to the bead of the tape in spaced relation, in a final scoop-forming operation through the action of said shaping and clamping dies, means for operating said strip-advancing means, said cutting device and said shaping and clamping dies in timed relation to the movement of the tape, means for locking said vertically reciprocable shearing die in gripping engagement with said strip to arrest

the advancement of this latter, and means operable at predetermined intervals for actuating said means for locking the shearing die during the advancement of the tape to provide blank spaces between adjacent groups of scoops clamped to said tape.

2. A machine for forming lengths of tape mounting groups of uniformly spaced scoops for slide fastener assembly, comprising a cutting device including a stationary and a vertically movable shearing die, shaping and clamping dies associated with said cutting device to provide a die station in said machine, means for intermittently advancing a strip of connected embryo fastener elements to said station, for successive severance therefrom of individual elements to be progressively introduced to said shaping and clamping dies for conversion into scoops, means for feeding a beaded tape through said die station in a continuous uniform step-by-step movement for the clamping of the severed elements to the bead of the tape in spaced relation, in a final scoop-forming operation, mechanism for operating said strip-advancing means, said cutting device and said shaping and clamping dies in timed relation to the movement of the tape, said operating mechanism comprising a driving shaft, a second shaft mounted in parallelism with said shaft and driven therefrom and a vertically reciprocable device operatively connected to the driving shaft for the actuation of said vertically movable shearing die, a pivoted member movable to a position for locking said vertically reciprocable device at the end of its downward stroke, to lock said vertically movable shearing die in its lowermost position in arresting contact with said strip to prevent advancement thereof, and means actuated by said second shaft for periodically moving said pivoted member to its die-locking position during the continuous movement of the tape to provide blank spaces between adjacent groups of scoops clamped to said tape.

3. A machine for forming lengths of tape mounting groups of uniformly spaced scoops for slide fastener assembly, comprising a cutting device including a stationary and a vertically movable shearing die, shaping and clamping dies associated with said cutting device to provide a die station in said machine, means for intermittently advancing a strip of connected embryo fastener elements to said station, for successive severance therefrom of individual elements to be progressively introduced to said shaping and clamping dies for conversion into scoops, means for feeding a beaded tape through said die station in a continuous uniform step-by-step movement for the clamping of the severed elements to the bead of the tape in spaced relation, in a final scoop-forming operation, mechanism for operating said strip-advancing means, said cutting device and said shaping and clamping dies in timed relation to the movement of the tape, said operating mechanism comprising a driving shaft, a second shaft mounted in parallelism with said shaft and driven therefrom and a vertically reciprocable device operatively connected to the driving shaft for the actuation of said vertically movable shearing die, a pivoted member movable to a position for locking said vertically reciprocable device at the end of its downward stroke, to lock said vertically movable shearing die in its lowermost position in arresting contact with said strip to prevent advancement thereof, means actuated by said second shaft for normally maintaining said pivoted member inoperative, and

means associated with said last-mentioned means for periodically moving said pivoted member to its die-locking position during the movement of the tape, to provide blank spaces between adjacent groups of scoops clamped to the tape.

4. A machine for forming lengths of tape mounting groups of uniformly spaced scoops for slide fastener assembly, comprising a cutting device including a stationary and a vertically movable shearing die, shaping and clamping dies associated with said cutting device to provide a die station in said machine, means for intermittently advancing a strip of connected embryo fastener elements to said station, for successive severance therefrom of individual elements to be progressively introduced to said shaping and clamping dies for conversion into scoops, said strip-advancing means comprising a reciprocable device and a rockable member associated therewith for frictionally engaging said strip during the movement of the reciprocable device in one direction, to intermittently advance the strip toward the die station, means for feeding a beaded tape through said die station in a continuous uniform step-by-step movement for the clamping of the severed elements to the bead of the tape in spaced relation, in a final scoop-forming operation, mechanism for operating said strip-advancing means and said respective dies in timed relation to the feeding of the tape, said operating mechanism comprising a driving shaft, a second shaft mounted in parallelism with said shaft and driven therefrom and a vertically reciprocable device operatively connected to the driving shaft for the actuation of said vertically movable shearing die, a pivoted member rotatable to a position for locking said vertically reciprocable device at the end of its downward stroke, to lock said vertically movable shearing die in its lowermost position in arresting contact with said strip to prevent advancement thereof, and means actuated by said driven shaft for periodically rotating said pivoted member to its die-locking position during the movement of the tape, to provide blank spaces between adjacent groups of scoops, the rockable member forming part of the strip-advancing means slidably traversing the strip toward and from the die station during the periods of arrested movement of the strip.

5. A machine for forming lengths of tape mounting groups of uniformly spaced scoops for slide fastener assembly, comprising coacting dies forming a cutting device, one of said dies being a shearing die reciprocable in a vertical plane, shaping and clamping dies associated with the cutting device to provide a die station in said machine, means for intermittently advancing a strip of connected embryo fastener elements to said die station, for successive severance therefrom, through the operation of said cutting device, of individual elements to be progressively introduced to said shaping and clamping dies for conversion into scoops in clamped engagement with a tape traversing said die station, means for feeding said tape through said die station in a continuous uniform step-by-step movement, mechanism for actuating said strip-advancing means, said shaping and clamping dies and said cutting device in timed relation to the movement of the tape, a rockable lever for engaging said vertically reciprocable shearing die and depressing the same to a position in gripping engagement with said strip, a shaft carrying cam means for actuating said lever, means for driv-

ing said shaft, a second shaft mounted in parallelism with said cam shaft and driven thereby, a member mounted for rotation in a horizontal plane to a position for locking said lever in movement-restraining engagement with said reciprocable shearing die to maintain the same in its depressed position, thereby arresting the advancement of the strip, and means actuated by said second shaft for periodically rotating said member to its lever-locking position during the feeding of the tape.

6. A machine for forming lengths of tape mounting groups of uniformly spaced scoops for slide fastener assembly, comprising a cutting device including a stationary and a vertically movable die, shaping and clamping dies associated with said cutting device to provide a die station in said machine, means for intermittently advancing a strip of connected embryo fastener elements to said station, for successive severance therefrom of individual elements to be progressively introduced to said shaping and clamping dies for conversion into scoops, means for feeding a beaded tape through said die station in a continuous uniform step-by-step movement for the clamping of the severed elements to the bead of the tape in spaced relation, in a final scoop-forming operation, mechanism for operating said strip-advancing means, said cutting device and said shaping and clamping dies in timed relation to the movement of the tape, said operating mechanism comprising a driving shaft, a second shaft mounted in parallelism with said shaft and driven therefrom and a vertically reciprocable device operatively connected to the driving shaft for the actuation of said vertically movable die, a pivoted member movable to a position for locking said vertically reciprocable device at the end of its downward stroke, to lock said vertically movable die in its lowermost position in arresting contact with said strip to prevent advancement thereof, a continuous element driven by said second shaft, rockable means operatively associated with said continuous element for normally holding said pivoted member inoperative, and cam means carried by said continuous element for movement therewith for periodically oscillating said rockable means to cause said pivoted member to periodically move to its die-locking position during the advancement of the tape.

7. A machine for forming lengths of tape mounting groups of uniformly spaced scoops for slide fastener assembly, comprising a cutting device including a stationary and a vertically reciprocable die, shaping and clamping dies associated with said cutting device to provide a die station in said machine, means for intermittently advancing a strip of connected embryo fastener elements to said die station for successive severance therefrom of individual elements to be progressively introduced to said shaping and clamping dies for conversion into scoops in clamped engagement with a tape traversing said die station, a driving shaft, a second shaft mounted in parallelism with said driving shaft, a third shaft disposed transversely of said shafts in torque-receiving connection with the driving shaft and in torque-transmitting connection with the second shaft, a cam on said third shaft for actuating said strip-advancing means, mechanism for operating said cutting device, a cam on said driving shaft for actuating said mechanism in timed relation with the advancement of the strip, mechanism for operating said shaping and

clamping dies comprising a pair of slides horizontally reciprocable transversely of the path of movement of the strip and carrying said dies, cams on said driving shaft and on said second shaft for conjointly actuating said slides in timed relation to the actuation of the cutting device, means for feeding the tape through the die station in a continuous uniform step-by-step movement for the clamping of the individual fastener elements to the tape in spaced relation, a cam on said driving shaft for actuating said tape-feeding means in timed relation to the advancement of the strip, means for locking said vertically reciprocable die in gripping engagement with the strip to arrest the advancement thereof, and a device operable at predetermined intervals during the movement of the tape for actuating said die-locking means, to provide blank spaces between adjacent groups of scoops clamped to the tape.

8. In a machine for forming lengths of tape mounting groups of uniformly spaced scoops for slide fastener assembly, in combination, a cutting device comprising a vertically reciprocable die, shaping and clamping dies associated with said cutting device to form a die station in said machine, means for intermittently advancing a strip of connected partially formed fastener elements to said die station for successive severance therefrom of individual elements to be progressively converted into scoops, means for feeding a tape through the die station in a continuous uniform step-by-step movement for the clamping of the severed elements to the tape in spaced relation, means including a plurality of shafts rotating at the same speed and cams on said shafts for actuating said strip-advancing means, said cutting device and said shaping and clamping dies in synchronism with the movement of the tape, mechanism for locking said vertically reciprocable die in gripping engagement with said strip to arrest the advancement of this latter, and a device operable at predetermined intervals dur-

ing the movement of the tape for actuating said die-locking means to provide blank spaces of like area between adjacent groups of scoops clamped to said tape.

- 5 9. A machine for forming lengths of tape mounting groups of uniformly spaced scoops for slide fastener assembly, comprising co-acting cutting dies, shaping and clamping dies associated with said cutting dies to provide a die station in said machine, means for intermittently advancing a strip of connected partially formed fastener elements to said die station, for successive severance therefrom of individual elements to be progressively introduced to said shaping and clamping dies for conversion into scoops in clamped engagement with a tape traversing said die station, means for feeding the tape through the die station in a continuous uniform step-by-step movement, mechanism for operating said cutting dies including a lever rockably mounted for movement in a plane at a right angle to the path of movement of said strip to the die station, a cam follower carried by said lever, a shaft mounted parallel to the path of movement of said strip, a cam on said shaft, yieldable means for maintaining said cam follower in engagement with said cam and means for driving said shaft to actuate said lever to engagingly operate said cutting dies in timed relation to the operation of the shaping and clamping dies and the movement of the tape through the die station, a shaft mounted in parallelism with said cam shaft and driven therefrom, means movable to a position for lockingly engaging said lever in its die-operating position to arrest the movement of said cutting dies in strip-engaging position, to prevent the advancement of the strip, and means propelled from said driven shaft for periodically actuating said movable means to their lever-locking position during the movement of the tape.
